Attorney.

UNITED STATES PATENT OFFICE.

FREDERICK OTT, OF NORRISTOWN, PENNSYLVANIA, ASSIGNOR TO A. T. BAKER & COMPANY, OF MANAYUNK, PENNSYLVANIA, A FIRM.

WOVEN PILE FABRIC.

1,327,683.

Specification of Letters Patent. Patented Jan. 13, 1920.

Application filed December 7, 1917. Serial No. 205,938.

To all whom it may concern:

Be it known that I, FREDERICK OTT, a citizen of the United States, residing at Norristown, in the State of Pennsylvania, have 5 invented a certain new and useful Improvement in Woven Pile Fabrics, whereof the following is a specification, reference being had to the accompanying drawings.

My invention relates to warp-piled fabrics of the double plush class which, when separated, form two textures which are alike.

The peculiar arrangement of the pile threads in accordance with my invention not 15 only produces pile facings of uniform density for the respective textures, but effects a more general interlocking of those threads with the backing threads, than in ordinary fabrics of said class, and, consequently, renders my improved fabric more firm and 20 durable than such ordinary fabrics.

Moreover, in such ordinary fabrics the ground threads are so arranged as to form plain cloth backs for said textures; whereas, 25 the ground threads in my fabric may be arranged, as hereinafter described, to form backing cloths for the respective textures, which are twilled, to render them more pliable than plain cloth, for furniture coverings and draperies.

My invention includes the various novel features of construction and arrangement hereinafter more definitely specified.

In the drawings: Figure I is a diagrammatic plan view of one pattern block of a double fabric embodying my invention; looking downward upon the back of the upper texture shown in Fig. II.

Fig. II is a diagrammatic longitudinal sectional view of the single texture, the back of which is shown in Fig. I; taken on the line II-II in that figure, to show the relatively staggered course of a pair of ground warp threads.

Fig. III is a plan view looking downward on the back of the upper texture shown in Fig. IV.

Fig. IV is a longitudinal edge view of said pattern block of the double fabric, showing the general course of the warp pile threads.

Fig. V is a diagram indicating the order

of shedding of both the ground and pile threads of said fabric.

In Figs. I and III, the horizontal rows 55 of squares represent warp ends and the vertical rows of squares represent picks of weft. Accordingly, in Fig. V, the horizontal lines represent warp ends and the vertical lines represent successive shedding operations; 60 and the order in which the respective warp ends are drawn up in the shedding operations represented by Fig. V is indicated by the X marks at the junctions of the lines in said figure. 65

The fabric illustrated is conveniently made with four backing ends and four pile ends in one dent; and with six backing heddles and six pile heddles, shedded in the order indicated in Fig. V; wherein the horizontal lines 1 to 6 inclusive indicate six warp ground threads, and the horizontal lines 8 to 13 inclusive indicate six warp pile threads. Said threads are thus identified in the other figures, which show patterns 70 each including twelve pile threads, which may be repeated transversely with respect to the respective fabrics, to any desired width. 75

It may be observed that said pattern of 80 twelve pile threads illustrated includes three series of said threads, each including two pairs of pile threads shedded alike, but unlike the adjoining series; but that, in the pattern of Figs. I to IV inclusive, said pile 85 threads are divided in groups of four, transversely with respect to the fabric, whereas, in the pattern disclosed and specifically claimed in my copending application Serial 233,626, filed May 10, 1918, as a division 90 of this case; said pile threads are divided in groups of two, transversely with respect to the fabric, by respective groups of ground threads.

In the patterns of Figs. I to V; the 95 groups 15 of said warp ground threads 1 to 6 extend only between said pile thread pairs which are shedded alike; so that each such group of four pile threads, extending between two such groups of warp ground 100 threads, includes two pairs of said pile threads, 8 to 13, which are shedded unlike. Said warp ground threads, 1 to 6, bind the weft threads 16 and 17 which are respec-

tively ultimately included in the upper and lower textures formed by cutting the double fabric on the line III—III in Fig. IV; and it may be observed that said pile threads are 5 interlocked with said ground threads so as to produce textures having the maximum of firmness and consequent durability when cut and separated as above contemplated. In that pattern, shown in Figs. I to V; I 10 prefer to arrange the ground warp threads in groups of 15, each consisting of four threads, divided in pairs to the respective textures, the members of which pairs, instead of being simultaneously shedded up and down respectively, are shedded successively, in relatively staggered relation to each other, and in a two up and one down manner with reference to the backs of the textures. However, I do not 15 desire to limit myself to the specific arrangement of the ground threads.

In the form of my invention illustrated, the warp threads are shedded in a reclining twill in the backs of the respective textures; 20 thus affording a desirable degree of pliability, despite the firmness of the fabrics. However, as they present a corresponding twilled effect in the respective pile facings formed by cutting said double fabrics between their backing textures, it is to be 25 noted that the twill is more visible in the fabric illustrated herein, than in the fabric illustrated in said divisional application. However, I do not desire to limit all of 30 my claims to either twilled arrangement or effect.

Therefore, I do not desire to limit myself to the specific construction or arrangement herein set forth, as it is obvious that various 40 modifications may be made therein without departing from the essential features thereof, as defined in the appended claims.

I claim:

1. A double woven pile fabric comprising opposite backing textures, each including ground weft threads and ground warp threads, and pile warp threads connecting said backing textures in spaced relation; said pile threads arranged in a pattern comprising twelve pile threads, repeated transversely with respect to the fabric, and including three series, each including two pairs of pile threads shedded alike, but unlike the adjoining series; said pile threads divided in 5 groups of four, transversely with respect to the fabric, by said warp ground threads, disposed in pairs between said pile thread pairs which are shedded alike; each such group of four including two pairs of pile threads which are shedded unlike; all of 10 said warp threads shedded in a reclining twill in said backing textures and presenting a corresponding twill in the respective facings formed by cutting said fabric between said backing textures; and said 15

ground warp threads being shedded two up and one down with reference to said backings.

2. A double woven pile fabric comprising opposite backing textures, each including ground weft threads and ground warp threads, and pile warp threads connecting said backing textures in spaced relation; said pile threads arranged in a pattern comprising twelve pile threads, repeated transversely with respect to the fabric, and including three series, each including two pairs of pile threads shedded alike, but unlike the adjoining series; said pile threads divided in groups of four, transversely with respect to the fabric, by said warp ground threads, disposed between said pile thread pairs which are shedded alike; each such group of four including two pairs of pile threads which are shedded unlike; all of 20 said warp threads shedded in a reclining twill in said backing textures and presenting a corresponding twill in the respective facings formed by cutting said fabric between said backing textures; and said 25 ground warp threads being shedded two up and one down with reference to said backings.

3. A double woven pile fabric comprising opposite backing textures, each including ground weft threads and ground warp threads, and pile warp threads connecting said backing textures in spaced relation; said pile threads arranged in a pattern comprising twelve pile threads, repeated transversely with respect to the fabric, and including three series, each including two pairs of pile threads shedded alike, but unlike the adjoining series; said pile threads divided in groups of four, transversely with respect to the fabric, by said warp ground threads, disposed between said pile thread pairs which are shedded alike; each such group of four including two pairs of pile threads which are shedded unlike; all of 30 said warp threads shedded in a reclining twill in said backing textures and presenting a corresponding twill in the respective facings formed by cutting said fabric between said backing textures; and said 35

4. A double woven pile fabric comprising opposite backing textures, each including ground weft threads and ground warp threads, and pile warp threads connecting said backing textures in spaced relation; said pile threads arranged in a pattern comprising twelve pile threads, repeated transversely with respect to the fabric, and including three series, each including two pairs of pile threads shedded alike, but unlike the adjoining series; said pile threads divided transversely with respect to the fabric, by said warp ground threads, disposed in pairs between said pile thread pairs which are shedded alike; each such group 40

including two pairs of pile threads which are shedded unlike; all of said warp threads shedded in a reclining twill in said backing textures and presenting a corresponding 5 twill in the respective facings formed by cutting said fabric between said backing textures; and said ground warp threads being shedded two up and one down with reference to said backings.

10 5. A double woven pile fabric comprising opposite backing textures, each including ground weft threads and ground warp threads, and pile warp threads connecting said backing textures in spaced relation; 15 said pile threads arranged in a pattern comprising twelve pile threads, repeated transversely with respect to the fabric, and including three series, each including two pairs of pile threads shedded alike, but unlike the adjoining series; said pile threads divided transversely with respect to the fabric, by said warp ground threads, disposed between said pile thread pairs which are shedded alike; each such group of four including 20 two pairs of pile threads which are shedded unlike; all of said warp threads shedded in a reclining twill in said backing textures and presenting a corresponding twill in the respective facings formed by cutting said fabric between said backing textures; and said ground warp threads being shedded two up and one down with reference to said backings.

6. A double woven pile fabric comprising opposite backing textures, each including ground weft threads and ground warp threads, and pile warp threads connecting said backing textures in spaced relation; said pile threads arranged in a pattern comprising 35 twelve pile threads, repeated transversely with respect to the fabric, and including three series, each including two pairs of pile threads shedded alike, but unlike the adjoining series; said pile threads divided transversely with respect to the fabric, by said warp ground threads, disposed between said pile thread pairs which are shedded alike; each such group of four including 40 two pairs of pile threads which are shedded unlike; all of said warp threads shedded in a reclining twill in said backing textures and presenting a corresponding twill in the respective facings formed by cutting said fabric between said backing textures.

7. A double woven file fabric comprising opposite backing textures, each including ground weft threads and ground warp threads, and pile warp threads connecting 45 said backing textures in spaced relation; said pile threads arranged in a pattern comprising twelve pile threads, repeated transversely with respect to the fabric; said pile threads divided in groups of four, transversely with respect to the fabric, by said

warp ground threads, disposed in pairs between said pile thread pairs which are shedded alike; each such group of four including two pairs of pile threads which are shedded unlike; all of said warp threads 70 shedded in a reclining twill in said backing textures and presenting a corresponding twill in the respective facings formed by cutting said fabric between said backing textures; and said ground warp threads being shedded two up and one down with reference to said backings.

8. A double woven file fabric comprising opposite backing textures, each including ground weft threads and ground warp 80 threads, and pile warp threads connecting said backing textures in spaced relation; said pile threads arranged in a pattern comprising twelve pile threads, repeated transversely with respect to the fabric; said pile 85 threads divided in groups of four, transversely with respect to the fabric, by said warp ground threads, disposed between said pile thread pairs which are shedded alike; each such group of four including two pairs 90 of pile threads which are shedded unlike; all of said warp threads shedded in a reclining twill in said backing textures and presenting a corresponding twill in the respective facings formed by cutting said 95 fabric between said backing textures; and said ground warp threads being shedded two up and one down with reference to said backings.

9. A double woven pile fabric comprising 100 opposite backing textures, each including ground weft threads and ground warp threads, and pile warp threads connecting said backing textures in spaced relation; said pile threads arranged in a pattern comprising 105 twelve pile threads, repeated transversely with respect to the fabric; said pile threads divided in groups of four, transversely with respect to the fabric, by said warp ground threads, disposed between said 110 pile thread pairs which are shedded alike; each such group of four including two pairs of pile threads which are shedded unlike; all of said warp threads shedded in a reclining twill in said backing textures and 115 presenting a corresponding twill in the respective facings formed by cutting said fabric between said backing textures.

10. A double woven pile fabric comprising opposite backing textures, each including ground weft threads and ground warp threads, and pile warp threads connecting said backing textures in spaced relation; said pile threads arranged in a pattern comprising 120 twelve pile threads, repeated transversely with respect to the fabric, and including three series, each including two pairs of pile threads shredded alike, but unlike the adjoining series; said pile threads divided in groups of four, transversely with 125 respect to the fabric, by said

respect to the fabric, by said warp ground threads, disposed in pairs between said pile thread pairs which are shedded alike; each such group of four including two pairs of 5 pile threads which are shedded unlike.

11. A double woven pile fabric comprising opposite backing textures, each including ground weft threads and ground warp threads, and pile warp threads connecting said backing textures in spaced relation; said pile threads arranged in a pattern comprising twelve pile threads, repeated transversely with respect to the fabric, and including three series, each including two pairs of pile threads shedded alike, but unlike the adjoining series; said pile threads divided in groups of four, transversely with respect to the fabric, by said warp ground threads, disposed between said pile threads which are shedded alike; each such group of four including two pairs of pile threads which are shedded unlike.

12. A double woven pile fabric comprising opposite backing textures, each including ground weft threads and ground warp threads, and pile warp threads connecting said backing textures in spaced relation; said pile threads arranged in a pattern comprising twelve pile threads, repeated transversely 25 with respect to the fabric, and including three series, each including two pairs of pile threads shedded alike, but unlike the adjoining series; said pile threads divided transversely with respect to the fabric, by 30 said warp ground threads, disposed in pairs between said pile thread pairs which are shedded alike; each such group of four including two pairs of pile threads which are shedded unlike.

40 13. A double woven pile fabric comprising
opposite backing textures, each includ-
ing ground weft threads and ground warp
threads, and pile warp threads connecting
said backing textures in spaced relation;
45 said pile threads arranged in a pattern com-
prising twelve pile threads, repeated trans-
versely with respect to the fabric, and in-
cluding three series, each including two
pairs of pile threads shedded alike, but un-
like the adjoining series; said pile threads
50 divided transversely with respect to the
fabric, by said warp ground threads, dis-
posed between said pile thread pairs which
are shedded alike; each such group of four
55 including two pairs of pile threads which
are shedded unlike.

14. A double woven pile fabric comprising opposite backing textures, each comprising ground weft threads and ground warp threads, and pile warp threads connecting said backing textures in spaced relation; said pile threads arranged in a pattern comprising twelve pile threads, repeated transversely with respect to the fabric; said pile threads divided in groups of

four, transversely with respect to the fabric, by said warp ground threads, disposed in pairs between said pile thread pairs which are shedded alike; each such group of four including two pairs of pile threads which 70 are shedded unlike.

15. A double woven pile fabric comprising opposite backing textures, each including ground weft threads and ground warp threads, and pile warp threads connecting said backing textures in spaced relation; said pile threads arranged in a pattern comprising twelve pile threads, repeated transversely with respect to the fabric; said pile threads divided in groups of four, transversely with respect to the fabric, by said warp ground threads, disposed between said pile thread pairs which are shedded alike; each such group of four including two pairs of pile threads which are shedded unlike. 85

16. A double woven pile fabric comprising opposite backing textures, each including ground weft threads and ground warp threads, and pile warp threads connecting said backing textures in spaced relation; 90 said pile threads arranged in a pattern comprising twelve pile threads, repeated transversely with respect to the fabric, and including three series, each including two pairs of pile threads shedded alike, but unlike the adjoining series; said pile threads divided in groups of four, transversely with respect to the fabric, by said warp ground threads, disposed in pairs between said pile thread pairs which are shedded alike; each 95 such group of four including two pairs of pile threads which are shedded unlike; all of said warp threads shedded in a twill in said backing textures.

17. A double woven pile fabric comprising 105 opposite backing textures, each including ground weft threads and group warp threads, and pile warp threads connecting said backing textures in spaced relation; said pile threads arranged in a pattern 110 repeated transversely with respect to the fabric, and including several similar series, each including two pairs of pile threads shedded alike, but unlike the adjoining series; said pile threads divided in groups of four, 115 transversely with respect to the fabric, by said warp ground threads, disposed in pairs between said pile thread pairs which are shedded alike; each such group of four including two pairs of pile threads which are 120 shedded unlike.

18. A double woven pile fabric comprising opposite backing textures, each including ground weft threads and ground warp threads, and pile warp threads connecting said backing textures in spaced relation; said pile threads arranged in a pattern repeated transversely with respect to the fabric, and including several similar series, each including two pairs of pile threads shedded 125 130

alike, but unlike the adjoining series; said pile threads divided in groups, transversely with respect to the fabric, by said warp ground threads, disposed between said pile thread pairs which are shedded alike; each such group including two pairs of pile threads which are shedded unlike.

19. A double woven pile fabric comprising opposite backing textures, each including ground weft threads and ground warp threads, and pile warp threads connecting said backing textures in spaced relation; said pile threads arranged in a pattern repeated transversely with respect to the fabric, and including several similar series, each including two pairs of pile threads shedded alike, but unlike the adjoining series; said pile threads divided in groups, transversely with respect to the fabric, by said warp ground threads, disposed in pairs between said pile thread pairs which are shedded alike; each such group including two pairs of pile threads which are shedded unlike.

20. A double woven pile fabric comprising opposite backing textures, each including ground weft threads and ground warp threads, and pile warp threads connecting said backing textures in spaced relation; said pile threads arranged in a pattern comprising twelve pile threads, repeated transversely with respect to the fabric, and including several series, each including two pairs of pile threads shedded alike, but unlike the adjoining series; said pile threads divided in groups of four transversely with respect to the fabric, by said warp ground threads, disposed in pairs between said pile thread pairs which are shedded alike; and said ground warp threads being shedded two up and one down with reference to said facings, and in staggered relation in said pairs.

21. A double woven pile fabric comprising opposite backing textures, each including ground weft threads and ground warp threads, and pile warp threads connecting said backing textures in spaced relation; said pile threads arranged in a pattern comprising twelve pile threads, repeated transversely with respect to the fabric, and including several series, each including two pairs of pile threads shedded alike, but unlike the adjoining series; said pile threads divided in groups of four, transversely with respect to the fabric, by said warp ground threads, disposed between said pile thread pairs which are shedded alike; and said ground warp threads being shedded two up and one down with reference to said facings, and in staggered relation.

22. A double woven pile fabric comprising opposite backing textures, each including ground weft threads and ground warp threads, and pile warp threads connecting said backing textures in spaced relation;

said pile threads arranged in a pattern, repeated transversely with respect to the fabric, and including several series, each including two pairs of pile threads shedded alike, but unlike the adjoining series; said pile threads divided in groups of four, transversely with respect to the fabric, by said warp ground threads, disposed between said pile thread pairs which are shedded alike; and said ground warp threads being shedded two up and one down with reference to said facings, and in staggered relation.

23. A double woven pile fabric comprising opposite backing textures, each including ground weft threads and ground warp threads, and pile warp threads connecting said backing textures in spaced relation; said pile threads arranged in a pattern, repeated transversely with respect to the fabric, and including several series, each including two pairs of pile threads shedded alike, but unlike the adjoining series; said pile threads divided in groups, transversely with respect to the fabric, by said warp ground threads, disposed between said pile thread pairs which are shedded alike; and said ground warp threads being shedded two up and one down with respect to said facings, and in staggered relation.

24. A double woven pile fabric comprising opposite backing textures, each including ground weft threads and ground warp threads, and pile warp threads connecting said backing textures in spaced relation; said pile threads arranged in a pattern repeated transversely with respect to the fabric, and including several similar series, each including two adjoining pairs of pile threads shedded alike; said pile threads divided in groups, transversely with respect to the fabric, by said warp ground threads, disposed in pairs between said pile thread pairs which are shedded alike.

25. A double woven pile fabric comprising opposite backing textures, each including ground weft threads and ground warp threads, and pile warp threads connecting said backing textures in spaced relation; said pile threads arranged in a pattern comprising twelve pile threads, repeated transversely with respect to the fabric, and including three series, each including two pairs of pile threads shedded alike, but unlike the adjoining series; said pile threads divided transversely with respect to the fabric, by said warp ground threads, disposed between said pile thread pairs which are shedded unlike; all of said warp threads shedded in a reclining twill in said backing textures and presenting a corresponding twill in the respective facings formed by cutting said fabric between said backing textures.

26. A double woven pile fabric comprising

6

ing opposite backing textures, each including ground weft threads and ground warp threads, and pile warp threads connecting said backing textures in spaced relation; 5 said pile threads arranged in a pattern comprising twelve pile threads, repeated transversely with respect to the fabric, and including three series, each including two pairs of pile threads shedded alike, but unlike the adjoining series; 10 said pile threads divided transversely with respect to the fabric, by said warp ground threads.

27. A woven pile fabric comprising a backing texture including ground weft threads and ground warp threads; and pile 15

warp threads forming a facing extending from said texture; said pile threads arranged in a pattern comprising twelve pile threads, repeated transversely with respect to the fabric, and including three series, 20 each including two pairs of pile threads shedded alike, but unlike the adjoining series.

In testimony whereof, I have hereunto signed my name at Philadelphia, Pennsylvania, this 26th day of November, 1917.

FREDERICK OTT.
